VICTOR H. HARBERT, OF CHICAGO, ILLINOIS, ASSIGNOR TO ILLINOIS RAILWAY EQUIPMENT COMPANY, OF CHICAGO, ILLINOIS, A CORPORATION OF ILLINOIS

LOCKING MEANS

Application filed July 3, 1931. Serial No. 548,563.

My invention relates to locking means more especially intended for fastening the hatch cover of a railroad refrigerator car; said means being adapted to receive the usual types of car seals at present employed.

The invention has for its object the provision of a locking device which may be readily applied to railroad cars at present in use without alteration in the hatch closure construction; and wherein the locking means is associated with the usual staple element of the hatch locking means so as to practically constitute an integral part thereof and removal of the locking element, after the staple has been secured in place, is made impossible and as a result the objections to constructions at present employed, because of loss and damage, have been overcome.

The objects and advantages of my invention will be readily comprehended from the following detailed description of the accompanying drawing wherein:

Figure 1 is a transverse sectional view of a portion of car-roof, hatch and cover, with my improved means in end elevation and shown in locking position.

Figure 2 is a top plan view of my improved means in locking position and a portion of a hatch cover.

Figure 3 is a perspective view of my improved locking means.

The hatch covers of railroad refrigerator cars are usually provided with hasps secured thereto so as to have the free ends of the hasps extend beyond the free or movable ends of the hatch covers; the hasps being formed to cooperate either with a swinging lever secured to the car-roof or with a suitable staple member secured to the car-roof adjacent to the free end of the hatch closure. The last mentioned type of fastening, namely the use of a staple, is generally employed with the hatch covers of meat shipping refrigerator cars wherein large hatch openings are provided and the hatch covers are arranged so they may be entirely removed when desired. In this type of refrigerator car, one end of the hatch cover shown at 10 is arranged beneath the running boards, a portion whereof is

shown at 11, thus making it impossible to raise this end of the hatch cover.

For purposes of exemplification, I have chosen to illustrate my invention with this type of refrigerator car hatch closure, although it will be understood that the invention is equally applicable to other types of hatch closures as well as for locking other devices.

In the drawing the hatch cover 10 is shown provided with a hasp 12, one end whereof is secured in place by bolts as at 13; the hasp intermediate of its ends being bent downwardly over the free end of the hatch cover and thence disposed laterally so as to extend substantially parallel with the car-roof, a portion whereof is shown at 14. The type of hasp here shown is intended for use with a staple which is usually bolted or otherwise fastened to the car-roof; the free end of the hasp being provided with a staple receiving slot as shown at 15 in Figure 2.

My invention contemplates a combined staple and locking element carrying member 16, which is adapted to be substituted for the ordinary staple at present employed.

My improved member 16 comprises a staple portion 17 having the apertured laterally disposed base 18 whereby the member is bolted or otherwise secured to the car-roof 14 adjacent to the hatch with the upstanding staple portion 17 disposed in a direction transversely of the car-roof so as to register with and pass through the slot 15 of the hasp 12 when the hatch cover 10 is in closed position.

The base 18, on one longitudinal side, preferably on the side disposed toward the hatch, is provided with an integral laterally disposed extension which terminates in the vertical enlargement or upwardly disposed head 19. This head 19 is provided with an opening 20 extending transversely therethrough and substantially parallel with the opening 21 in the staple portion 17. One side of the opening 20, namely the upper side, is provided with the upwardly disposed slot 22 for the purpose hereinafter described.

My improved locking element is preferably in the nature of a U-shape hook 23 provided

with a short leg 24 which is intended to pass through the hole 21 of the staple portion 17, while the long leg or side of the hook member 23 is slidingly mounted in the opening 20 in the head 19.

The long leg or side of the hook member 23, adjacent to its ends, is provided with a pair of lateral enlargements or lugs 25, 26. The lugs 25 and 26 are arranged in alignment 10 and are of configuration and dimensions to match the slot portion 22 of the opening in the head 19, so as to permit the long leg or side of the hook member 23 to be inserted through the opening 20 of the head 19 when 15 the hook member is positioned with the lugs 25 and 26 arranged in registering alignment with the slot 22.

It is apparent from the construction shown that the aligned position of the lugs 25 and 20 26 with the slot 22 can only be obtained when the hook member 23 is moved to a position where the short leg or side 24 will be disposed in a plane beneath the base 18 of the device, and therefore a position which can be obtained 25 only before the device is secured to the car-roof, as the lugs 25 and 26 are arranged substantially in the same plane as the intermediate portion and the short leg or side 24; while the slot 22 in the head 19 30 is disposed upwardly as shown in Figure 3.

The hook member 23 is inserted through the opening 20—22 before the device is applied to the car-roof; the insertion being accomplished by swinging the short leg 24 35 downwardly beneath the head 19 so as to present the lug 25 of the long leg or side upwardly where it will register with the slot portion 22 of the opening 20 in the head 19.

After the lug 25 has been passed through 40 the opening in the head 19, the hook member is then swung upwardly, which causes the lugs 25—26 to be moved ninety or more degrees away from the slot 22 and hence prevents withdrawal of the hook member 23.

As soon as the base portion 18 of the device 45 has been secured to the car-roof by bolts or other fastening means passed through the holes 27, 27, it is apparent that the hook member 23 cannot then be swung into a position 50 where the lugs will register with the slot and hence the locking hook becomes an integral part of the device and accidental dissociation of the elements is impossible.

The lug 25 prevents withdrawal of the 55 hook member; while the lug 26, which is located to the opposite side of the head 19, is intended to properly position the short leg or side 24 relative to the staple 17 so that opposite ends of a diagonally arranged slot 60 28 in leg 24 will be positioned to opposite sides of the staple member 17 when the hook member is in locking position. The slot 28, which extends through the hook member, is intended to receive the usual seal, generally 65 consisting of a wire or metal strip, the ends

whereof are brought together, after the wire has been inserted through the slot, and then soldered or sealed together.

To lock the hatch closure, the hood member 23 is slid along in the head 19 until the lug 25 engages the side of the head 19, at which time the short leg 24 will be out of engagement with and free of the staple 17, thus allowing the end of the hasp 12 to be passed over the staple 17. The short leg or side 24 of the hook member is then passed through the staple 17 above the end of the hasp and the usual car seal (not shown) is then arranged as previously stated.

What I claim is:

1. Locking means of the character described comprising a single piece member provided with an attaching base; an upstanding staple portion disposed transversely of and integral with the base; a laterally disposed extension integral with one side of the base and terminating in an upstanding enlargement provided with an opening therethrough arranged parallel with the opening in the staple portion and a vertically arranged slot communicating with the opening in the enlargement; and a U-shaped locking member with sides of unequal length, the long side of the member being slidingly mounted in the enlargement while the short side is adapted to pass through the opening in the staple portion, the long side of the locking member adjacent opposite ends being provided with parallel extensions disposed in the same plane as the short side of the locking member whereby movement of the locking member in locking and unlocking directions is controlled, the slot in said enlargement being disposed beyond the arc of movement of the locking member when the single piece member is secured in place.

2. Locking means of the character described comprising an upstanding head portion provided with an opening transversely therethrough of irregular formation; a U-shaped locking bolt having legs of unequal length, the long leg being slidable in the opening of said head and provided adjacent opposite ends with laterally disposed enlargements arranged in alignment with each other and in the same horizontal plane as the short leg, said enlargements being formed to match the irregular part of said opening, said enlargements and the matching portion of the opening being arranged at an angle to each other relative to the oscillatory movement of the locking bolt with the matching portion of the opening arranged beyond the arc of movement of the bolt when the locking means is secured in place; and a staple whose opening is disposed parallel with the opening in said head portion and adapted to receive the short leg of the bolt.

3. Locking means of the character described comprising a single piece member

formed to constitute an upstanding apertured staple portion and an extension disposed laterally from one side of the staple portion and terminating in an apertured head, the aperture in the head involving a radial slot; and a U-shaped bolt having legs of unequal length, the short leg being adapted to pass through the staple portion while the long leg at opposite ends has lugs disposed laterally and parallel with each other and with the short leg, said long leg being slidably mounted in said head and one of said lugs adapted to pass through said slot before the member is secured in place, the slot being disposed beyond the arc of normal movement of the legs whereby sliding movement of the bolt is limited and withdrawal of the bolt from said head made impossible after the member has been secured in place; the short leg of the bolt being provided with a diagonally arranged slot whose ends are adapted to be disposed at opposite sides of the staple portion, when the bolt is in full locking position, to receive a sealing medium.
